DESIGN FOR A FIRE EXTINGUISHER

Lucien Sulzer, Chicago, Ill.

Application October 21, 1944, Serial No. 115,901

Term of patent 14 years

(Cl. D16—2)

To all whom it may concern:

Be it known that I, Lucien Sulzer, a citizen of the United States of America, residing at 432 West Superior Street, Chicago, Illinois, have invented a new, original, and ornamental Design for a Fire Extinguisher, of which the following is a specification, reference being had to the accompanying drawing, forming a part thereof.

Referring now to the drawing, Fig. 1 is a side elevational view of a fire extinguisher embodying my new design; Fig. 2 is a rear elevational view and Fig. 3 is a front elevational view thereof.

I claim:

The ornamental design for a fire extinguisher, substantially as shown.

LUCIEN SULZER.
